TUNABLE COAXIAL CAVITY RESONATOR
Kenneth E. Hancock, Roxboro, Quebec, Canada, assignor
to Canadian Marconi Company, Montreal, Quebec,
Canada

Filed Sept. 3, 1965, Ser. No. 484,973
1 Claim. (Cl. 333—82)

This invention is concerned with tunable cavity resonators and is particularly directed to cavities of the coaxial type having capacity loading.

A reduction in the length of coaxial cavities which are tuned over a range of frequencies by adjustment of the length of the inner conductor can be achieved by fixing a capacity loading cup coaxially on that end wall opposite the wall supporting the inner conductor. The loading cup, cylindrical in configuration, has an inner diameter somewhat larger than the free end of the coaxial inner conductor. In tuning the device the inner conductor penetrates beyond the lips of the cup member, and in advancing increasingly loads the inner conductor with end capacity.

The above-described arrangement has the disadvantage in some applications that the change of frequency obtained is a quite non-linear function of the axial displacement of the inner conductor. It is an aim of this invention to substantially reduce this non-linearity.

According to the invention a tunable coaxial resonator of the type wherein the free end of the coaxial inner conductor is adjustable axially to enter within the confines of a cylindrical cup-shaped capacity loading member is characterised in that the wall of said cup-shaped member is provided with a pair of diametrically opposite semi-circular cut-outs the radius of which is substantially the same as the inner radius of said cup-shaped member and whose centres lie in the plane of the cup rim.

The invention will be more particularly described with reference to the accompanying drawings in which:

2

FIGURE 1 shows in cross-section a tunable coaxial cavity resonator in accordance with the invention; and

FIGURE 2 shows the tuning laws of a resonator in accordance with the invention as compared with that of a prior art cavity.

Referring to FIGURE 1 there is shown a tunable coaxial cavity resonator comprising the known construction of a cylinder 1, end walls 2 and 3, a fixed section of coaxial inner conductor 4, an axially moveable inner conductor section 5 with actuating means such as screw 6, and a capacity loading cup 7. In accordance with the invention the cup 7 is provided with two diametrically opposite semi-circular cut-outs, one of which, 8, is visible in FIGURE 1. As is shown, the cut-outs have a radius which is substantially the same as that of the inner radius of cup 7, and are oriented such that their centres lie on a common diameter in the plane of the cup rim.

In FIGURE 2 is shown the tuning law for such a cavity with and without the cut-outs 8. It will be seen that by the use of cut-outs 8 in accordance with the invention a substantial improvement in the linearity of the tuning law is achieved.

I claim:

25 A tunable coaxial resonator of the type wherein the free end of the coaxial inner conductor is adjustable axially to enter within the confines of a cylindrical cup-shaped capacity loading member is characterised in that the wall of said cup-shaped member is provided with a pair of diametrically opposite semi-circular cut-outs the radius of which is substantially the same as the inner radius of said cup-shaped member and whose centres lie in the plane of the cup rim.
